UNITED STATES PATENT OFFICE.

WALTER ROWLANDS, OF MONTREAL, CANADA.

RAILWAY-SWITCH STAND.

SPECIFICATION forming part of Letters Patent No. 534,761, dated February 26, 1895.

Application filed August 22, 1894. Serial No. 521,049. (No model.)

To all whom it may concern:

Be it known that I, WALTER ROWLANDS, of the city of Montreal, in the district of Montreal and Province of Quebec, Canada, have 5 invented certain new and useful Improvements in Railway-Switch Stands; and I do hereby declare that the following is a full, clear, and exact description of the same.

This invention relates to switch stands, provided with automatic locking parts, and has for its object an improvement in the general construction of such stands, and particularly in the pedestal or base thereof, the target rod connection, the operating lever, and the locking parts of the locking bar. For full comprehension however of the invention reference must be had to the annexed drawings forming a part of this specification, in which like symbols indicate corresponding parts, 20 and wherein—

Figure 1 is a side elevation of the switch stand, adapted to be used for yard work, but capable of having added to it the post and other parts suitable for main line work, portions of such additional parts being indicated by dotted lines. Fig. 2 is a view of the stand similar to Fig. 1, but with switch unlocked. Fig. 3 is a front elevation of the switch stand with parts locked. Fig. 4 is a horizontal section of stand on line xx Fig. 3. Fig. 5 is a plan view of the table portion and base of the stand, and Fig. 6 a detail view partly broken away of the lower portion of the stand and the locking parts of the locking bar.

A is a metal pedestal or base, hollow as formerly and provided with the usual bottom flange A', flat top or table portion A², lateral projection A³, and in this case formed with a vertical recess A⁴ in its rear side to receive 35 the necessary post b indicated by dotted lines in Figs. 1 and 4 when the stand is used for main line work, the post being preferably secured in place by bolt b' passing through it and the pedestal.

The laterally projecting portion of the table A² is perforated as usual for the vertical locking spindle C upon the upper end of which is keyed the lift casting or head piece D. This lift casting has an upwardly projecting socket 40 or holder section D', formed with a square vertical recess or socket D², to receive the squared ends of either a long target rod, used

in connection with the post b, or a short one as used in yard work, a portion of rod being indicated by the dotted lines D³. This squared connection between the target rod and lift casting is necessary in order to positively insure the proper rotation of the rod, as in some cases where the circular connection is used, it has happened that the retaining screw has 55 worked loose, with the result that the target rod has not been turned in order to exhibit the proper light or side of the target corresponding with the position of the switch. The usual set screw D⁴ is of course used to prevent accidental vertical displacement of the target rod.

The operating lever or handle C* is preferably made hollow with lifting cam head e' pivoted as usual to the lift casting and in this case formed with a downwardly projecting lip or shoulder C' on its under side in such a position that as the handle is turned down the inclined side C² of such lip will bear beneath the lower edge of the table portion A² of the 70 base and thus serve to force downward the lift casting and with it the locking spindle C and the locking bar F, to be presently described, so that any obstruction in the form of dirt, &c., that might be in the way of the 75 downward movement of the locking bar will be overcome.

To further prevent any possibility of an accumulation of dirt interfering with the downward movement of the locking bar as is the 80 case when such bar is formed with a downward projection to enter notches in the lock plate G in advance of the stand, I form an upward projection G' on such plate and two openings F' in the bar, either of which is 85 adapted to receive the projection as the bar is forced downward.

As a ready means of effecting an operative connection between the locking bar and the vertically movable locking spindle, I extend 90 as at N' the outer end of the crank N on the lower end of such spindle so that the inner end of the locking bar instead of requiring to be curved upward and connected with the spindle above the lock casting K can remain 95 straight and be located between the upper surface of such extension and the under side of the lock casting K.

Reverting to the operating lever I may say

that it has been found desirable to determine the precise distance of its throw to one side or the other in shifting the rails of the switch, and I accordingly form limiting stops l l , on 5 the upper surface of the table A^2 , into contact with which it is thrown, and in order that the lift casting D which is wider than the lever, may not engage the stops and so prevent the lever being thrown the full distance, so its under side is cut away as at D^5 to avoid contact with them.

What I claim is as follows:

1. A switch stand having its pedestal formed with a vertical recess in its side for the purpose set forth.
- 15 2. In a switch stand, the combination with

the lock plate G , having upward projection G' , of the locking bar, formed with openings F' , for the purpose set forth.

3. In a switch stand, the combination with 20 the locking bar thereof, and the operating spindle, of the crank on such spindle having its free end extended to support said locking bar, and the lock casting on such spindle adapted to bear upon and retain such bar in 25 place for the purpose set forth.

Montreal, August 7, 1894.

WALTER ROWLANDS.

In presence of—

WILL P. MCFEAT,
FRED. J. SEARS.
